BRONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 10, 1923. Serial No. 637,929.

My invention relates to railway traffic controlling apparatus, and particularly to apparatus of the type wherein alternating current or currents are supplied to the trackway for the control of train carried governing mechanism.

In one arrangement of apparatus of the type mentioned, it has been suggested to employ the usual track circuit current, that is, the current which energizes the track relays, as one of the currents for controlling the train carried governing mechanism, such control being effected by this current through the medium of receiving appliances at the front end of the train. When this is done, it is obvious that the source of track circuit current must always be connected across the rails ahead of a train.

In the case of a double track railroad in which traffic on each track normally moves in one direction, only, this requirement is readily met in so far as movements in the normal direction are concerned because the source of track circuit current for each section is then connected across the rails adjacent the exit end of each section in accordance with standard practice in automatic block signaling. In the case of single track roads, however, it is necessary for trains to proceed over the track in both directions, and in such instances with only the trackway apparatus thus far mentioned, trains moving in one direction would not receive track circuit current. One feature of my invention is the provision of means, located in the trackway, for connecting a source of track circuit current across the rails at either end of the section, thus permitting train movements in both directions.

I will describe one form of railway traffic controlling apparatus embodying my invention, and will then point out the novel features thereof in claims.

The accompanying drawing is a diagrammatic view showing one form and arrangement of railway traffic controlling apparatus embodying my invention.

Referring to the drawing, the reference characters 2 and 2^a designate the track rails of a railway over which traffic moves in both directions. These rails are divided by means of insulated joints 1 into a plurality of insulated track sections A—B, B—C, etc. Each track section is provided with a track trans-

former designated by the reference character T with an exponent corresponding to the location and having a secondary winding 5 connected across the rails adjacent the left hand end of the section. Interposed between one terminal of this secondary winding 5 and the track rails 2 is an impedance 7, one function of which is to limit the output of the transformer when its terminals are short-circuited by the wheels and axles of a train occupying the associated section. A similar track transformer designated by the reference character U with an exponent corresponding to the location is provided for each section and has its secondary winding 83 connected across the rails adjacent the right hand end of the section. An impedance 85 is connected between this impedance and one rail 2^a of the associated section. Each section is provided with two track relays designated by the reference characters R and D 75 with exponents corresponding to the locations, which relays are located at the left hand and right hand ends of the section respectively. Associated with each relay R is a directional relay K, a line relay H, and a stick relay S. A repeater relay, designated by the reference character P with an exponent corresponding to the location is associated with each relay D.

Referring particularly to section A—B, 85 the relay R^A is connected, by means of wires 9 and 10, across the rails at the left hand end of the section, and so it is also connected across the secondary winding 5 of transformer T^A. In order to protect the relay, an impedance 8 is connected in series therewith, which impedance may be short-circuited when transformer T^A is not energized. The directional relay K^A is provided with a circuit which passes from the right hand terminal of the secondary winding 56 of a line transformer F^A, through wires 55 and 54, back contact 52—51 of relay S^A, wire 15, relay K^A, and wires 13, 14, 17, 19 and 60 back to the left hand terminal of 100 secondary winding 56 of transformer F^A. This circuit is closed only when relay S^A is de-energized. The primary winding 57 of line transformer F^A is constantly connected to two line wires 3 and 3^a fed by a generator 105 4. A second circuit is provided for relay K^A which passes from the right hand terminal of secondary winding 56 of transformer F^A,

through wires 58, 23 and 21, front contact 28—29 of track relay R^A , wire 87, directional relay K^A , wire 13 and back to the left hand terminal of secondary winding 56 as before. 5 This circuit is closed only when relay R^A is energized. It is clear, therefore, that relay K^A is energized when relay R^A is energized, or relay S^A is de-energized. Line relay H^A is provided with a circuit which 10 passes from the right hand terminal of the secondary winding 56 of the line transformer F^B for the section next in advance, through wires 55, 58 and 59, front contact 36—37 of relay H^B , wire 39, back contact 48—49 of relay S^B , wire 64, front contact 70—71 of relay D^B wire 27, front contact 25—26 of relay R^A , wire 16, line relay H^A , and wires 18, 19, 60 and 86 back to the left hand terminal of secondary winding 56 of 15 transformer F^B . An auxiliary circuit is provided for relay H^A which passes from the right hand terminal of secondary winding 56 of transformer F^B , through wires 55 and 53, front contact 47—48 of relay S^B , wire 64, front contact 70—71 of relay D^B , wire 27, front contact 25—26 of relay R^A , wire 16, winding of relay H^A and wires 18, 19, 60 and 86 back to the left hand terminal of secondary winding 56 of transformer F^B . 20 25 It is clear, therefore, that relay H^A is energized when relays R^A , D^B and H^B are energized and relay S^B is de-energized; or when relays R^A , D^B and S^B are energized. Stick relay S^A is provided with a pick-up circuit 30 which passes from the right hand terminal of secondary winding 56 of transformer F^A through wires 63 and 67, back contact 73—74 of relay D^A , wire 69, front contact 34—35 of relay H^A , wires 41 and 43, relay S^A , and wires 42 and 60, back to the left hand terminal of secondary winding 56 of transformer F^A . This relay is also provided with a stick circuit which passes from the right hand terminal of secondary winding 56 of transformer F^A , through wires 58 and 59, back contact 36—38 of relay H^A , wire 40, front contact 45—46 of relay S^A , wire 44, relay S^A , and wires 42 and 60 back to the left hand terminal of winding 56 of transformer F^A . It follows that when relay D^A is de-energized and relay H^A is energized, the relay S^A will be picked up, and that it will thereafter stick up through its own front contact while relay H^A is de-energized. The impedance 8 is provided with a shunt which comprises wires 11 and 12 and back contact 32—33 of relay R^A whereby this impedance is short-circuited when relay R^A is de-energized. The primary winding 6 of track transformer T^A is supplied with alternating current through a circuit passing from the right hand terminal of secondary winding 56 of transformer F^A through wires 58, 23 and 22, front contact 30—31 of relay K^A , wire 62, winding 6, and wires 14, 17, 19 and 60 back to the left hand terminal of secondary winding 56 of transformer F^A . This circuit is closed only when relay R^A is energized in which case section A—B is supplied with track circuit current from its left hand end by means of transformer T^A . The energizing circuit for relay D^B passes from rail 2 through wire 82, relay D^B , wire 76, back contact 78—79 of relay P^B , and wire 68 back to the rail 2. 70 Evidently this circuit is closed only when relay P^B is de-energized. Relay P^B is provided with a circuit which passes from the right hand terminal of secondary winding 56 of transformer F^A , through wires 55 and 54, front contact 52—50 of relay S^A , wire 24, back contact 25—90 of relay R^A , wire 27, back contact 70—72 of relay D^B , wire 75, relay P^B , and wires 88, 61, 17, 19 and 86, back to the left hand terminal of secondary winding 56 of transformer F^A . This circuit is closed only when relays R^A and D^B are both de-energized and relay S^A is energized. A circuit is provided also which 80 passes from the right hand terminal of secondary winding 56 of transformer F^B , through wires 63 and 66, front contact 77—80 of relay R^B , wire 81, primary winding 84 of transformer U^B , and wires 61, 17, and 19, back to the left hand terminal of secondary winding 56 of transformer F^B . This circuit is closed only when relay P^B is energized in which case the rails of section A—B are supplied with track circuit current from transformer U^B . The operation of the entire system is as follows: Normally, that is, in the absence of trains, each relay K is closed and each relay P is open so that track circuit current is supplied to each section at the left hand end, and track relays R and D are both in the track circuits and are both energized. I will now assume a train to be moving from left to right. As this train enters the section to the left of point A, track relay D^A will be de-energized thus closing the circuit for stick relay S^A through contact 73—74. Since the relay H^A is energized and contact 34—35 thereon is closed, stick relay S^A will be picked up. As the train enters section A—B 105 110 both track relays R^A and D^B will be de-energized. The opening of the front contact of these relays de-energizes line relay H^A which opens its front contacts and interrupts the pick-up circuit for stick relay S^A . This relay does not open however because it is now energized over its own front contact and a back contact on the line relay H^A . The closing of back contacts 25—90 and 70—72 on relays R^A and D^B respectively completes the circuit for relay P^B which circuit passes over front contact 52—50 of stick relay S^A . Relay P^B therefore closes and by so doing disconnects track relay D^B from the track circuit by opening 120 125 130

- its back contact 78-79 and at the same time connects a source of energy to the primary 84 of track transformer U^B by closing its front contact. But relay K^A is de-energized since one of its circuits was opened by the opening of back contact 52-51 of stick relay S^A and the other of its circuits was opened by the de-energization of track relay R^A and the consequent opening of front contact 28-29 thereon. The de-energization of relay K^A disconnects energy from the primary winding of transformer T^A by the opening of front contact 30-31 and closes the shunt around impedance 8 by closing back contact 32-33. Under these conditions, then, energy is supplied to the track circuit from transformer U^B which is located in advance of the train. As the train clears the point A, track relay D^A closes but the opening of its back contact does not de-energize the stick relay S^A which is held closed by energy over the circuit through its front contact and back contact 36-38 of relay H^A . As the train passes out of the section A-B at point B, energy flows from transformer U^B through the rails and energizes relay R^A . The opening of its back contact 25-90 de-energizes relay P^B , which opens, re-connecting relay D^B to the track circuit and disconnecting energy from transformer U^B . In the meantime however the closing of front contact 28-29 has energized relay K^A . The shunt around impedance 8 is therefore opened and energy is re-connected to the transformer T^A . The operation of the apparatus in section B-C is exactly similar to that just described for section A-B and therefore stick relay S^B will now be energized and as a result, line relay H^A will now be energized over front contact 48-47 of stick relay S^B and front contacts of relays R^A and D^B . Stick relay S^A is therefore de-energized thus restoring the apparatus associated with section A-B to normal. When the train has proceeded out of section B-C, relay S^B is de-energized and the control of line relay H^A now passes over back contact 48-49 of stick relay S^B and front contact 36-37 of relay H^B thus restoring the section A-B to its normal condition. One feature of my invention is the provision of means for delaying the opening of the stick relay till after the control of relay H is completed.
- 55 I will now assume a train to be moving from right to left and to enter section B-C. Both track relays R^B and D^C will be de-energized, thus opening the circuit for line relay H^B at their front contacts. But the opening of relay H^B does not affect any of the other relays so the transformer U^C will remain disconnected from the track and the transformer T^B will continue to feed the rails of the section. As the train passes into section A-B relays R^A and D^B will both be de-energized. Now when the rear of the train clears point B, energy from transformer T^B picks up both relays R^B and D^C and completes the circuit for relay H^B . But since relay D^B is de-energized, the closing of contact 34-35 on line relay H^B completes the pick-up circuit for stick relay S^B which closes but this is of no consequence as all of the circuits which this relay controls are open at other points. As the train clears point A relay D^B is energized thus de-energizing stick relay S^B and restoring section B-C to normal condition. It is clear, therefore, that for traffic moving from right to left the track circuit current is always supplied from ahead of the train.
- 10 Although I have herein shown and described only one form of railway traffic controlling apparatus embodying my invention, it is understood that various changes and modifications may be made therein within the scope of the appended claims without departing from the spirit and scope of my invention.
- 15 Having thus described my invention, what I claim is:
1. Railway traffic controlling apparatus comprising a section of railway track, a source of track circuit current normally connected across the rails adjacent the left hand end of said section, a track relay connected across the left hand end of said section, a second source of track circuit current located at the right hand end of said section but normally disconnected therefrom, a second track relay normally connected across the rails adjacent the right hand end of said section, a normally de-energized stick relay arranged to be energized by a train approaching said section from the left and to remain energized while such train is passing through the section, a directional relay controlled in part by said first track relay, and in part by said stick relay for disconnecting said first source from the rails of said section, and a repeater relay controlled by said track relays and by said stick relay for connecting said second source with and disconnecting said second track relay from the rails of the section.
- 20 2. In combination, a section of railway track, a first source of current normally connected with the rails adjacent one end of said section, a second source of current adjacent the other end of the section but normally disconnected from the rails, a normally de-energized relay, means controlled by a train approaching said section from one direction but not from the other direction for energizing said relay before the train enters the section, a track relay for said section, means controlled by said track relay for keeping said normally de-energized relay energized while a train which has caused it to become energized is passing through the

section, a directional relay controlled by said normally de-energized relay and by said track relay for disconnecting said first source from the track rails when a train 5 passes through the section in the first mentioned direction, and means controlled by said normally de-energized relay and by said track relay for connecting said second source with the rails of the section.

10 3. Railway traffic controlling apparatus comprising a section of railway track, a source of track circuit current normally connected across the rails adjacent the left hand end of said section, a track relay connected across the left hand end of said section, a second source of track circuit current located at the right hand end of said section but normally disconnected therefrom, a second track relay normally connected across 20 the rails adjacent the right hand end of said section, a line relay controlled in part by said track relays, a stick relay controlled in part by said line relay, a repeater relay controlled by said stick relay and said track relays, a directional relay having an energiz- 25

ing circuit including a source of energy and a front contact on said first track relay and a second energizing circuit including a source of energy and a back contact on said stick relay, means controlled by said directional relay for disconnecting said first source, and means controlled by said repeater relay for connecting said second source and disconnecting said second track relay. 30 35

4. In combination, a forward and a rear section of railway track, a track relay connected across the rails at the left hand end of said rear section, a second track relay connected across the rails at the right hand end of said rear section, a line relay for said forward section, a stick relay for said forward section controlled in part by said line relay, and a line relay for said rear section controlled by said track relays, said first line 40 45 relay and said stick relay.

In testimony whereof I affix my signature.

RONALD A. McCANN.
